UNITED STATES PATENT OFFICE.

HARRY T. ANDERSON, OF BUTLER, PENNSYLVANIA, ASSIGNOR TO HARRY VISSERING AND COMPANY, OF CHICAGO, ILLINOIS, A CORPORATION OF ILLINOIS.

MANUFACTURE OF DRAWBAR-YOKES.

1,401,748.

Specification of Letters Patent. Patented Dec. 27, 1921.

Application filed February 25, 1920. Serial No. 361,078.

To all whom it may concern:

Be it known that I, HARRY T. ANDERSON, a citizen of the United States, and a resident of Butler, in the county of Butler and State 5 of Pennsylvania, have invented certain new and useful Improvements in the Manufacture of Drawbar-Yokes, of which the following is a full, clear, and exact description.

The invention relates to the manufacture 10 of drawbar yokes and its object is to provide an improved method of forging one-piece yokes.

The invention consists in the several novel 15 features hereinafter set forth and more particularly defined by claims at the conclusion hereof.

In the drawings: Figure 1 is an elevation and Fig. 2 is a plan of a channeled blank from which the yoke is forged. Fig. 3 is an 20 elevation and Fig. 4 is a section showing the blank after it has been cut to form draft-gear openings and key-slots and after its ends have been trimmed. Fig. 5 is an elevation and Fig. 6 is a section of the blank after the end- 25 portions have been bulged outwardly and shaped and the flanges have been notched. Fig. 7 is an elevation of the blank after its flanges have been shaped for overlapping. Fig. 8 is a plan and Fig. 9 is a horizontal section 30 of the finished yoke. Fig. 10 is a section on line 10—10 of Fig. 9.

The yoke is forged from a longitudinal bar 10, preferably of rolled or wrought steel. Said bar has top and bottom flanges 11 and 35 12 and a connecting web 13. This bar is of sufficient length to form both sides of a yoke and may, if desired, be cut from long stock. Four openings 16 are cut through the web 13, as shown in Fig. 3. These openings are 40 spaced apart to leave a vertical columnar portion 17, medially of the blank, between the flanges. These openings are of sufficient area to receive one side of a draft-gear. The portion 17 is adapted to be formed into the 45 back of a yoke, integral with the sides. A key-slot is cut through the web adjacent each end of the blank. The end-portions of the flanges are cut off and the web is trimmed on convergent lines, as at 18, to form rounded 50 narrowed ends. The metal adjacent the

outer ends of each key-slot 19 is swaged or upset, as shown at 20, to form an enlarged or reinforced bearing for a key in the slot. Next, the web portions 26, which are outwardly of the draft-gear openings 16, are 55 bulged outwardly and inclined away from the plane face of the blank. Medially, the flanges are notched or cut away, as at 28.

Next, one portion 11^a of flange 11 and a portion 12^a of the flange 12 will be forged 60 into offset relation with respect to remaining portions 11^b and 12^b respectively, as shown in Fig. 7. Next, the blank will be bent and doubled transversely on a medial line to form sides in juxtaposition and with the key-slots 65 and draft gear openings transversely aligned. This bending operation will bring the flange-portion 11^a and 11^b in lapped relation and the lower flange-portions 12^a and 12^b will be similarly lapped. The front portions of the 70 lapped flanges are then secured together by rivets 30, and then the yoke will be finished.

The bulged web-portions 26 and adjacent lapped flange-portions form a coupler-shank 75 pocket. Openings 16 are adapted for the lateral insertion of members of tandem draft-gear, as well understood in the art. The edges of these openings form abutments for the draft-gear members.

The invention is not to be understood as restricted to the details set forth, since these may be modified within the scope of the appended claims, without departing from the spirit and scope of the invention.

Having thus described the invention, what 85 I claim as new and desire to secure by Letters Patent, is:

1. That improvement in making railway draft-gear yokes which consists in cutting a plurality of draft-gear openings in a bar of 90 metal, forming the ends of the blank for keying to a coupler shank, forging offset marginal flanges on the blank, and bending and doubling the blank to bring the draft gear openings into transverse alinement.

2. That improvement in making railway draft gear yokes which consists in cutting a plurality of draft-gear openings in the web of a marginally flanged bar of metal, forming the ends of the blank for keying to cou- 100

pler shank, offsetting portions of the flanges, and bending and doubling the blank to bring the flanges in lapped relation and to bring the openings into transverse alinement.

- 5 3. That improvement in making railway draft-gear yokes which consists in cutting a plurality of draft-gear openings in a bar of

metal, forming the ends of the blank for keying to a coupler shank, forging the offset marginal flanges on the blank, bending and 10 doubling the blank to bring the draft gear openings into transverse alinement and securing the lapped flanges together.

HARRY T. ANDERSON.
